(57) **CLAIM**

The ornamental design for a stamping pad design for decorative finishes using interfitting repeating designs, as shown and described.

DESCRIPTION

FIG. 1 is a top plan view of a stamping pad design for decorative finishes using interfitting repeating designs embodying my invention;

FIG. 2 is a side elevational view of a first side thereof taken on line 2—2 in FIG. 1, the thickness of the pad backing panel and the height of the projections below the pad layer being uniform across the entire pad backing panel and the other side views being projections of the design shown in FIG. 3; and,

FIG. 3 is a bottom plan view thereof with the projection raised from the pad backing panel shown in black for illustrative purposes only.
